[57] ABSTRACT

An assembly for aiding self-locomotion of a wearer of leg cast or other foot immobilizing device whereby a selective sliding motion may be utilized in place of the conventional walking motion. The assembly includes a resilient retainer having apertures into which inserts of a low coefficient of friction, which protrude slightly above the retainer, are placed. Engagement of the retainer with the surface over which locomotion is to be effected permits a sliding of the limb; however, when a predetermined weight is applied to the assembly, the resiliency of the retainer allows the inserts to be pressed inwardly into their aperture such that the surrounding retainer provides a non-slip, frictional engagement with said surface. Alternatively, each insert could have its own resilient support mounted within its aperture to allow for the relative movement between it and the retainer.

GLIDE ASSEMBLY

BACKGROUND OF THE INVENTION

This is a continuation-in-part of application Ser. No. 848,295 filed Aug. 7, 1969 now U.S. Pat. No. 3,633,573.

This invention relates to an assembly for permitting the wearer of a walking-type cast, or of an orthopedic shoe, or the like, selectively to slideably engage his encased foot with the floor and, thereby, allow him easier locomotion. More particularly, the invention relates to an assembly which includes glide inserts of low coefficient of friction material which are inserted into, and are removable from, apertures in a resilient retainer of high coefficient of friction material, with the assembly adaptable for use as the heel assembly or sole assembly affixed to the foot-bottom of a walking-type leg cast, or as the principal component of an orthopedic shoe, and the like.

It is to be noted that the terms "walking-type leg cast," "walking leg cast," "walking cast," and "cast" as used above and as hereinafter used, are intended, for the purpose of this application, to be synonymous and interchangeable, and are also intended to include a foot cast, an ankle cast, and the like. What is meant by use of any of the above terms or their equivalents is that at least the foot, but not necessarily the toes, is immobilized in a conventional plaster cast having, in whole or in part, a base or bottom serving as a sole.

In the prior art, individuals having a cast-bound foot moved under their own power by lifting the foot up and then lowering it, in a walking motion, thereby placing their full weight on the foot and the cast. Alternatively, they used canes and crutches of various modified forms to assist them in moving under their own power. In doing so, they favored the encased foot by placing all or most of their weight on the other foot and on the cane or crutches used, with resultant strain on the other foot, on the hand grasping the cane, and, in using crutches, on the hands grasping the crutch, the arms, and the armpits.

The art advanced substantially with the advent and the use of a floor-engageable peg at the foot-bottom of the cast, since the user of such a walking cast could walk in many instances without the use of canes or crutches, by lifting and then lowering his foot, with the weight being placed on the peg. However, despite the availability and use of canes, crutches, floor-engageable pegs, and other prior and present art devices, the individual who sustains a foot, ankle or leg break or fracture which allows or requires a walking-type cast is, at best, in the unfortunate position of being able to move under his own power only with strain, resultant fatigue, great inconvenience, and some lack of safety, with the degree of these distinct disadvantages increasing with the length and weight of the cast.

Our invention significantly advances the state-of-the-art by permitting individuals who have a cast-bound foot to move with a sliding motion, rather than a walking motion, with the sliding being much easier, less awkward, less fatiguing, and relatively safer than walking; and, in addition, our invention promotes recovery, principally by minimizing weight-bearing on the cast-bound foot, and thereby permits the earlier return of the individual to his normal activities. When weight is applied to the structure of our invention, a conventional friction surface is provided to inhibit sliding and

provide stability. Thus, an undesired rotation is not necessary to engage the frictional surface with the floor.

SUMMARY OF THE INVENTION

This invention relates to means for permitting self-locomotion by the wearer of a walking-type leg cast by sliding, rather than by walking, with said means being readily adaptable for use as a heel assembly of the walking-type cast, the platform or sole assembly of such a cast, and as the principal component of an orthopedic shoe, and the like.

An object of this invention is to permit an individual wearing a walking-type leg cast, or having a cast-bound foot, or wearing an orthopedic shoe or the like, to move under his own power by selectively sliding his encased foot along the floor and enabling a frictional engagement with the floor, when desired, without a rotation of the foot.

Another object of this invention is to permit the individual to accomplish the above-described self-locomotion with much more ease, much less fatigue, and in the relatively safer manner than is possible with past or present state-of-the-art devices.

These objects, and still other and related ones, of this invention will become readily apparent after a consideration of the description of the invention and reference to the drawings.

DESCRIPTION OF THE DRAWINGS

FIG. 1 is a side elevation view, partly in cross-section, of a preferred embodiment of the invention;

FIG. 2 is the bottom view of another preferred embodiment of the invention;

FIG. 3 is a side elevation view, in cross-section, of the embodiment shown in FIG. 2;

FIG. 4 is the bottom view of still another preferred embodiment of the invention;

FIG. 5 is a side elevation view, in cross-section, of the embodiment shown in FIG. 4;

FIG. 6 is the bottom view of yet another preferred embodiment of the invention;

FIG. 7 is a side elevation view, partly in cross-section, of the embodiment shown in FIG. 6; and

FIG. 8 is a side elevation view, in cross-section, of alternative preferred embodiments of the invention.

DESCRIPTION OF THE PREFERRED EMBODIMENTS

With reference to FIG. 1, there is shown, in side elevation and partly in cross-section a preferred embodiment in the form of a heel assembly 10 which includes a floor-engageable glide insert 11 of material having a low coefficient of friction (i.e., having good sliding properties), such as a durable plastic material which additionally can be easily fabricated and molded, preferably nylon or teflon, with said glide insert 11 securely inserted or fitted into, but removable from, suitably configurated aperture 12 of a resilient heel 13, which is of material of a high coefficient of friction, preferably rubber, and with said heel 13 having, if desired, a serrated or otherwise roughened base 14 and a lip or flange 15. Also shown therein is walking cast 16 with wall 17 and base or bottom 18. The lower surface of lip 15 of heel assembly 10 abuts the upper surface of cast wall 17; and heel assembly 10 is made integral to cast 16, with heel 13 and glide insert 11 protruding slightly

from the bottom of cast 16. The resiliency of the heel is controlled such that upon a predetermined pressure exerted by the wearer, the glide inserts will be pressed inwardly and the high friction material will be in engagement with the floor to inhibit sliding.

In FIGS. 2 and 3, wherein the same reference numbers designate the same components, is shown another embodiment, heel assembly 20, in, respectively, a bottom view and a side elevation cross-sectional view. Heel assembly 20 includes floor-engageable glide inserts 21 and 22 of material having a low coefficient of friction (i.e., having good sliding properties), such as a durable plastic material which additionally can be easily fabricated and molded, preferably nylon or teflon, with said glide inserts 21 and 22 securely inserted into or fitted into, but removable from any suitably configurated apertures 23 and 24, respectively, of resilient heel 25, which is of material of a high coefficient of friction, preferably rubber, and with said heel 25 having, if desired, a serrated or otherwise roughened base 26 and a lip or flange 27. Not shown, in the interest of maintaining simplicity and clarity, is the walking cast, such as 16, FIG. 1, to which heel assembly 20 is made integral, with heel 25 and glide inserts 21 and 22 protruding slightly from the bottom of the cast.

In FIGS. 4 and 5, wherein the same reference numbers designate the same components, is shown still another preferred embodiment of the invention in the form of a platform or sole assembly 30 in, respectively, a bottom view and a side elevation cross-sectional view. Sole assembly 30 includes a plurality of floor-engageable glide inserts, such as 31-36 inclusive, of material having a low coefficient of friction (i.e., having good sliding properties), such as a durable plastic which additionally can be easily fabricated and molded, preferably nylon or teflon, with each said glide insert, such as 31, FIG. 5, securely inserted into or fitted into, but removable from, its suitably configurated individual aperture, such as 37, FIG. 5, of the plurality of apertures, such as 37-42 inclusive, FIG. 4, of a resilient platform or sole 43 which is of material of a high coefficient of friction, preferably rubber, and which has lip or flange 44. Also shown in FIG. 5, in cross-section and partly fragmented, is walking cast 45, with base or bottom 46, to which sole assembly 30 is made integral by being position wholly within said cast 45, and being affixed thereto, with the bottom surface of sole 43 and the bottom of glide inserts, 31-36 inclusive exposed and external of cast 45.

In FIGS. 6 and 7, wherein the same reference numbers designate the same components, is shown yet another preferred embodiment of the invention in the form of an orthopedic shoe 50, in, respectively, a bottom view and a side elevation cross-sectional view. Orthopedic shoe 50 includes: a resilient platform or sole 51 of material of high coefficient of friction, preferably rubber, to which is affixed by suitable means at the periphery thereof means for permitting entry, retention, and, when desired, release of the cast-bound foot, such as a top 53 of flexible material, preferably canvas, and laces or ties (not shown) connected to said top 53. Sole 51 has a plurality of apertures, such as 54-62 inclusive, FIG. 6, into which are securely inserted or fitted a plurality of floor-engageable glide inserts, such as 63-71 inclusive, FIG. 6, made of material of a low coefficient of friction, such as a durable plastic which additionally can be easily fabricated and molded, preferably nylon

or teflon. The guide inserts, such as 54, FIG. 7, are removable from their suitably configurated individual apertures, such as 63, FIG. 7. The upper surface of sole 51 is, preferably, raised at the rear or heel portion 52.

With reference to FIGS. 1-7, inclusive, glide inserts (such as 11, FIG. 1; 21 and 22, FIGS. 2 and 3; 31-36 inclusive, FIGS. 4 and 5; and 63-71 inclusive, FIGS. 6 and 7) are, individually, preferably in the form of a cylinder of two diameters, with the narrower diameter being inserted wholly into the suitably configurated aperture (such as 12, FIG. 1) and the wider diameter protruding a short distance from the bottom of the heel (such as 14, FIG. 1, and 25, FIGS. 2 and 3) and from the bottom of the platform or sole (such as 43, FIGS. 4 and 5, and 51, FIGS. 6 and 7), with the bottom surface of the wider diameter portion of the glide insert engaging and making contact with the floor. Although the glide inserts are shown in FIGS. 1-7 to be flat-bottomed, this is by way of illustration only. The bottom of the glide inserts (such as 11, FIG. 1; 21 and 22, FIGS. 2 and 3; 31-36 inclusive, FIGS. 4 and 5; and 63-71 inclusive, FIGS. 6 and 7), may be of any suitable shape or form, including the point-contact type. In all of the embodiments thus far described the material in which the glide inserts are placed is of sufficient resiliency, at least in the portion immediately surrounding each insert, such that upon a predetermined pressure exerted by the wearer, the glide insert would be pressed inwardly and the high frictional material would then be in engagement with the floor to inhibit sliding. This can be effected without a rotation of the sole and heel portions.

With reference to FIG. 8, therein is shown in a side elevation cross-sectional view still other preferred embodiments of the invention. The embodiment 80 is a means for permitting self-locomotion by the wearer of a walking-type leg cast by a sliding movement, rather than by walking, and includes a retainer 81 of material of a high coefficient of friction, preferably rubber, for use as a heel, platform, sole, or the like with apertures, such as 82 and 83, having at the upper terminus, such as 84 and 85, a wider diameter to accept and hold a glide insert, such as 90, made of material of a low coefficient of friction, such as a durable plastic which additionally can be easily fabricated and molded, preferably nylon or teflon. Each glide insert, such as 90, is configurated in the form of a cylinder of three diameters, with the two diameters, such as 91 and 92, being at either end and the narrowest diameter, such as 93, being therebetween. The upper wider diameter 92 of glide insert 90 fits into the upper terminus, such as 84 and 85, of the aperture, such as 82 and 83. The narrowest diameter 93, which is the midportion of glide insert 90, fits into, and is positioned wholly within, the narrow diameter of the aperture. The other wide diameter portion 91 of glide insert 90 protrudes a short distance from the bottom of retainer 81 and, thereby, engages and makes contact with the floor. It is to be noted that a glide insert, such as 90, may be removed from the respective aperture, such as 83, in which it is positioned, although in use the glide insert is securely fitted into and held by the mating configuration of the aperture. As in the case of the glide inserts shown in FIGS. 1-7, the glide insert 90, FIG. 8, need not be flat-bottomed, as shown. The bottom may be of any suitable shape or form, including the point-contact type.

The insert arrangement thus far described relative to FIG. 8 could have the retainer 81 of resilient material as described relative to the previously presented embodiments or, alternatively, that portion immediately surrounding each aperture could be of a resilient material such that upon the exertion of a predetermined pressure on the assembly by the wearer the glide inserts 90 would be pressed inwardly to enable the sole or heel portions beyond the glides to be in frictional engagement with a floor, thereby inhibiting sliding without requiring a rocking or rotary motion of the foot to effect the frictional material in engagement with the floor.

Although the glides have been thus far described in frictional engagement with the apertures, it is contemplated that, as illustrated at the right of FIG. 8, the glide 100 could be retained in an aperture as illustrated at 101 by means of a spring 102 attached to the glide by friction, pinning or other conventional means. The spring 102 is secured in the upper, larger diameter portion by expansion into the groove at 103. In this case, the controlled resiliency of the sole and heel portions would not have to be specified since the spring would effectively allow for the movement of the glide insert into the retainer element at 104.

Additionally, as shown in phantom with respect to glide insert 90, a ball bearing 95 may be provided within the glide which forms a rack therefor. If the ball bearing were utilized, the protrusion of the glide from the retainer would be less so that the ball bearing only protrudes slightly from the retainer. In any case, the various types of glide could be used in combination or alone with the various embodiments of the retaining means.

MODE OF OPERATION OF THE PREFERRED EMBODIMENTS

The operation of each of the preferred embodiments is based upon the phenomena that it is easier (i.e., less fatiguing, less awkward, and the like) for an individual having a cast-bound foot to slide on it, rather than to walk on it. It is further advantageous for the wearer of one of the preferred embodiments, previously described, to avoid a rocking action of his foot in order to provide engagement of the frictional container with the floor. More specifically, in the embodiments the combination of the low coefficient of friction material glide inserts fitted into a retainer of material of high coefficient of friction with both, or either, of the different coefficient of friction materials being simultaneously floor-engageable at the option of the user, permits a controlled sliding motion, rather than walking, which is a new and unexpected result not heretofore contemplated in the art.

Embodiments 10, FIG. 1, and 20, FIGS. 2 and 3, are affixed by and during the molding of the foot cast, such as 16, FIG. 1, to the bottom 18, FIG. 1, of the cast 16. More specifically, the lower surface of the flanged portion, such as 15, FIG. 1, of heel 13, FIG. 1, and 27, FIGS. 2 and 3, of heel 25, FIGS. 2 and 3, is made to abut with the upper surface of the bottom 18 of cast 16, FIG. 1. Each of these two embodiments (heel assembly 10, FIG. 1, and heel assembly 20, FIGS. 2 and 3) are made integral to the cast, such as 16, FIG. 1, while the cast is being molded. The heel of each embodiment, such as 13, FIG. 1, and 25, FIGS. 2 and 3, with the glide insert(s), such as 11, FIG. 1, and 21 and 22, FIG. 2, in heel apertures, such as 12, FIG. 1, and 23 and 24,

FIGS. 2 and 3, is made to protrude slightly from the bottom of the cast. The specific position of the heel embodiment, such as 10, FIG. 1, and 20, FIGS. 2 and 3, at the bottom 18 of the cast 16, FIG. 1, and the location of the heel aperture(s) with the glide insert(s), is dependent upon, and determined by, the respective position and location which will permit easy sliding motion of the glide insert(s) and, yet, will result in sufficient braking force from the rubber heel, such as 13, FIG. 1, 10 with its serrated base, such as 14, FIG. 1, to stop unchecked sliding, in the unlikely event that that should occur. This is controlled by application of the weight of 15 an individual with a cast embodying our invention, as depicted in FIGS. 1 and 2, merely slides his cast-bound foot on the glide insert(s), such as 11, FIG. 1, and 21 and 22, FIGS. 2 and 3, rather than lifting and then lowering the cast-bound foot, as he would do if he were using a walking movement. Nevertheless, the individual may, should he desire to do so, walk with the cast, rather than using the intended sliding movement. In fact, since the glide inserts are removable for replacement and the like, they may be removed in a particular instance if the removal facilitates walking.

Embodiment 30, FIGS. 4 and 5, which is our invention in the form of a platform or sole assembly, is inserted in the cast, such as 45, FIG. 5; and, as the bottom, such as 46, FIG. 5, of the cast is being molded to the wearer's foot, the entire sole assembly 30, except 30 for the bottom portion thereof, is covered with plaster. Thereby, embodiment 30 is built into, and made integral to, the cast, but with the bottom surface of platform or sole 43 and the bottom surface of glide inserts 31-36 inclusive exposed and external of the cast, so as 35 to be floor-engageable. In this platform-type or sole-type embodiment 30 of the invention, as in the case of the heel-type embodiments 10 and 20 shown in FIGS. 1-3 inclusive, the individual wearer merely slides his cast-bound foot on the glide inserts, rather than lifting and then lowering his cast-bound foot, as he would do if he were using a walking movement. He may elect, however, to walk, rather than to use a sliding motion; and, additionally, he may remove the slide inserts, if 40 such removal would assist him in walking. As a related matter, configuration of the glide inserts, although already discussed in part, will be further discussed in describing the modification shown in FIG. 8. As in the previous embodiments application of a predetermined pressure to the unit enables retraction of the slides resulting in engagement of the frictional material with the floor.

Embodiment 50, FIGS. 6 and 7, which is in the form of an orthopedic shoe, may be used to encase a cast bound foot, or to encase an injured foot when normal walking would be too much strain. The individual slips or inserts his foot, which may not be in a cast, into the shoe 50, FIG. 6, through an appropriate opening and retaining means, such as canvas top or uppers 53 having laces or ties (not shown). The wearer of embodiment 50 merely slides his encased foot on the guide inserts, such as 63-71 inclusive, of the shoe, rather than using a walking movement. The raised heel 52, FIG. 7, improves the sliding motion; and, additionally, prevents the glide inserts, such as 63-71 inclusive, from pressing into the wearer's heel, which is of particular importance if the wearer has an injured foot which is not in a cast. Weight on the assembly produces the same re-

sult as in the previously described embodiments. If a walking, rather than a sliding, movement is desired, the glide inserts may be removed from the apparatus, such as 54-62 inclusive, FIG. 6. As in the case of embodiment 30, FIGS. 4 and 5, the configuration of the glide inserts will be further discussed in describing the modifications of FIG. 8.

Embodiments 80, FIG. 8, show various configuration of glide inserts 90 and 100 and of the respective apertures 83 and 101 which may be advantageously used in embodiment 30, the sole assembly, FIGS. 4 and 5, and in embodiment 50, the orthopedic shoe, FIGS. 6 and 7. In those two aforementioned embodiments, it may be necessary for the wearer's comfort to keep the glide insertion length short, or to have a very thick platform or sole. Under these or similar circumstances, a glide insert and aperture configurated, respectively, as 90 and 83 and 100 and 101 may be advisable to prevent the loss of a glide insert, although such a loss is so remote as to be unlikely. Nevertheless, at the risk of being overcautious in the interest of the wearer's safety, wide diameter portion 92 and 103 in the nature of a flange, of glide insert 90 and spring 102 insures positive retention and would alleviate any apprehensions, real or otherwise, of the loss of a glide insert configurated as shown in FIGS. 1-7, inclusive. The embodiments of FIG. 8 function as in all other described embodiments such that when weight is applied the pressure on the glide causes it to withdraw within the aperture and allow for engagement with the retaining means with the floor.

While there has been shown and described the fundamental features of our invention, as applied to particular embodiments, it is to be understood that this is by way of illustration only and is not intended as a limitation, and that various substitutions and omissions may be made by those skilled in the art without departing from the spirit of the invention. For example, although the glide inserts or second components of the assembly have been defined as having round shank portions, square or any other regular shape could be utilized to provide for positive reinsertion of a glide within its similarly shaped aperture in the first component of the assembly to present a new wearing surface after the glide has achieved some wear in a first position. Also, the head portion need not be of larger diameter. Only that portion of the glide to contact the floor need be of material of low coefficient of friction. Thus, the configuration of the glide inserts, the number of glide inserts used, the relative spacing from each other, the means by which they are retained, and the positioning of the glide inserts in the retaining means may be varied to provide a sliding movement which is most beneficial to the wearer of the embodiment, depending upon the particular foot, ankle, and leg injury which resulted in the foot being cast-bound. The retainer or first component could be made with a cylindrical or other shaped rubber plug having aperture therein which is inserted and made fixed to the remainder of the retainer in

order to provide more easily the desired resiliency in the area around the glide or second component of the assembly. If desired, a backing material or plate may be provided to insulate the foot of a wearer from feeling localized pressure in the area above the glides. Additionally, embodiment 50, FIG. 7, could be in the form of a boot, a moccasin, a loafer, a slipper, and the like, rather than in the form of a conventional shoe.

What we claim is:

1. An assembly adapted for use with the foot of a human wearer comprising
  - a first component which is of material of a high coefficient of friction to inhibit sliding when in contact with a floor, said component having at least one aperture therein;
  - a second component having a shank portion secured within an aperture of said first component, and having a head portion providing a lower coefficient of friction than that of said first component to permit sliding when in contact with a floor, said head portion protruding a short distance from said first component; and
  - means responsive to a predetermined pressure applied to said second component to allow said second component to withdraw within said first component so as to protrude therefrom in order to allow for selective contact by the said first component with a floor.
2. An assembly as defined in claim 1 including means secured to said first component for its attachment to the foot of a human wearer.
3. An assembly as defined in claim 1 wherein said last mentioned means is a spring secured to both of said first and second components.
4. An assembly as defined in claim 1 wherein said last mentioned means comprises a section of resilient material around said aperture.
5. An assembly as defined in claim 1 wherein said head portion of said second component has a ball bearing mounted therein to provide the protrusion from said first component.
6. An assembly adapted for use with the foot of a human wearer comprising
  - a first component which is of material of a high coefficient of friction to inhibit sliding when in contact with a floor and having at least one portion having resiliency,
  - an aperture in said portion, and
  - a second component having a shank portion secured within said aperture, and having a head portion providing a lower coefficient of friction than that of said first component to permit sliding when in contact with a floor, said head protruding a short distance from said first component;
  - the resiliency of the resilient portion being such as to allow a retraction of said second component upon application of a predetermined force thereto.
